UNITED STATES PATENT OFFICE.

OSCAR LINDQUIST AND ANDRO PISARCIK, OF VANDERGRIFT, PENNSYLVANIA,
ASSIGNORS TO AMERICAN SHEET & TIN PLATE COMPANY, OF PITTSBURGH,
PENNSYLVANIA, A CORPORATION OF NEW JERSEY.

APPARATUS FOR POLISHING ROLLS.

1,165,009.

Specification of Letters Patent. Patented Dec. 21, 1915.

Application filed June 21, 1913. Serial No. 775,043.

To all whom it may concern:
Be it known that we, OSCAR LINDQUIST, a citizen of the United States, and ANDRO PISARCIK, a subject of the King of Hungary and Emperor of Austria, both residing at Vandergrift, in the county of Westmoreland and State of Pennsylvania, have invented a new and useful Apparatus for Polishing Rolls, of which the following is a 10 specification.

Our invention relates to apparatus used in connection with rolling mills in maintaining the surfaces of the reducing rolls of such mills in operative condition, and the invention more particularly relates to the construction and arrangement of a novel apparatus designed for use for polishing the surfaces of the rolls of hot mills used in rolling sheets and plates. After such rolls 20 have been in use for some time, rough spots frequently appear on the surfaces thereof, which must be removed as formed to prevent the surfaces of materials rolled thereafter being defective. Heretofore, it has 25 been the practice to remove rough spots appearing on the surfaces of the rolls during the operation of the mill, by holding a grinding block against the peripheral portions of the roll upon which such rough 30 spot or spots appear, while the rolls are being rotated. The output of such mills has been very materially increased in recent years and, owing to the added duty of the rolls, it is necessary to repolish or remove 35 rough spots from the rolls with much greater frequency. As the body of the rolls of such mills are crossed, *i. e.*, are not true cylinders, and as the contour of these rolls changes at different times in the rolling operations, a single polishing block equal in 40 length to the length of the barrel or body of the roll is not adapted for use with such rolls.

One object of our invention is to provide 45 a roll polishing apparatus adapted for use during the operation of the mill by the use of which the polishing operations are facilitated, the time required in polishing or restoring the roll surfaces is reduced, and

the necessity of delay in the operation of the 50 mill for the purpose of polishing the rolls is avoided and overcome.

Another object of our invention is to provide a roll polishing apparatus having novel means whereby the polishing operation is 55 readily effected at any and all points in the length of the barrel or body portion of the rolls while the rolls are operatively mounted in the roll housings.

A further object of this invention is to 60 provide improved apparatus for polishing rolls having novel means whereby the polishing block is moved into and out of operative engagement with the roll and is maintained in polishing position as desired 65 or found necessary.

Still further objects of our invention will appear as the invention is more fully disclosed hereinafter and pointed out in the 70 appended claims.

Referring to the drawings forming part of this specification Figure 1 is a sectional end elevation of a two-high hot mill showing a roll polishing apparatus constructed and arranged and applied for use in accordance with our invention. Fig. 2 is a plan showing the construction of the means employed in supporting the polishing block and guide therefor and for holding the polishing block in operative engagement 80 with the rolls of the mill. Fig. 3 is a sectional end elevation showing in detail the construction of the polishing block and the holder or guide therefor and the slideway or support in which the polishing block and 85 guide are movably secured in accordance with this invention. Fig. 4 is a detail plan of the holder for the polishing block shown in Fig. 3.

In the accompanying drawings the number 90 2 designates one of the pair of roll housings of a sheet or plate mill which are secured in spaced apart relation upon the usual housing shoes 3, 3 by means of housing bolts 4. Mounted in bearings which are 95 positioned in the windows 5 of the roll housings in the usual known manner are the rolls 6 and 7.

The bottom roll 6 is positively driven by an engine or other prime mover (not shown) in the usual known manner, the wabbler on one neck of the bottom roll 6 being detachably connected by a spindle and coupling boxes to the prime mover. The top roll is rotated by contact with the bottom roll or with metal being reduced between the rolls.

10 Pivotedly secured to the inner sides of the roll housings by means of cap-bolts 8 or studs, or equivalent means, are the pairs of swinging arms 9 and 10, 11 and 12. The inner or highest ends of the arms 9 and 10 are rigidly secured to the ends of a guide bar 13 having a dovetail slot 14 therein which extends from end to end thereof. The arms 9 and 10 have slots 15 therein which embrace or engage the cap-bolts 8 in 15 the side of the housing, forming the pivots for the arms, these slots providing a convenient means for readily removing and replacing the apparatus in operative position.

20 The rear or lowermost end of the arm 9, in which arm the slot 15 is located at a point intermediate its ends, is provided with a handle 16 by which the arms are swung manually as will be described later.

25 The swinging arms 11 and 12, which are 30 on the opposite side of the rolls from that on which the arms 9 and 10 are applied, have slots 15 by which the arms are held in swinging position on cap-bolts 8 and the inner or highest ends of these arms are fastened to the ends of a guide bar 13 having a longitudinally extending dovetail slot 14.

35 The outer or lower end of the arm 11 is bent to form a treadle 17 by means of which the arms 11 and 12 are conveniently rocked 40 in swinging the apparatus into and out of operative engagement with the lower roll 6.

45 Secured in the dovetail slot 14 in each guide bar 13 is a slide block 18 which is arranged to move in the slot 14 from end to end of the guide bar so as to traverse the entire length of the barrel or body of the roll 6 or 7 with which it is intended for use. Mounted in the recess in the slide blocks 18 are polishing blocks 19 formed of carborundum or similar material, rods or rivets 50 being fastened in the ends of the slide blocks.

55 Each of the slide blocks 18 is provided with a lug or ear 21 which is arranged to project beyond the side of the guide bars 13 into convenient position to be pushed or struck by the operator in moving the slide blocks across the length of the guide bars 13.

60 In the operation of our improved roll polishing apparatus a slide block 18 having a polishing block 19 secured therein is mounted in the dovetailed slot 14 in each slide bar 18. The swinging arms 9 and 10, 11 and 12 are then secured in place between

the inner sides of the roll housing 2, the slots 15 in these arms embracing or engaging 65 with the cap-bolts 8 on the sides of the housings so that the arms 9 and 10, 11 and 12 may be swung to move the polishing blocks 19 into engagement with the roll surfaces. When continued operation of the rolling 70 mill makes it necessary to polish the rolls the slide block 18 having polishing blocks 19 therein is moved lengthwise in the dovetailed slot 14 by means of the lug or ear 21 until the polishing block engages with the 75 portion of the periphery of the roll it is desired to polish. The weight of the swinging arms and the guide bar secured thereto holds the polishing block in operative engagement with the face of the roll and the 80 rotation of the roll causes the rough spots to be gradually removed therefrom. As the operation of the mill continues the polishing blocks will be moved lengthwise across the face thereof to bring the polishing block 85 into operative engagement with the entire surface of the roll so that by properly adjusting the polishing block in the slide bar 13 the rolls can be maintained in a polished condition throughout the extended operation of the rolls.

89 The advantages of our invention will be apparent to those skilled in the art. The apparatus is simple and is easily kept in repair. By its use the rolls are maintained in polished condition while still permitting the continued operation of the mill, and the necessity of stopping the operation of the mill to remove rough spots from the surfaces of the rolls is avoided and overcome.

95 Modifications in the construction and arrangement of the parts may be made without departing from our invention as defined in the appended claims.

100 We claim:

105 1. In roll polishing apparatus, the combination with a roll, of a polishing block adapted to engage the roll surface, a slide block to which the polishing block is removably secured, a guide bar on which the slide 110 block is adjustably mounted, means on the slide block for moving said slide block in moving the polishing block across the face of the roll, and pivoted arms on the guide bar whereby the polishing block is held by 115 gravity in polishing engagement with the roll face, said pivoted arms being loosely connected to the pivot support therefor.

120 2. In roll polishing apparatus, the combination with a roll, of a polishing block adapted to engage the roll surface, a slide block to which the polishing block is removably secured, a guide bar on which the slide 125 block is adjustably mounted, means on the slide block for moving said slide block in moving the polishing block across the face

of the roll, pivoted arms on the guide bar whereby the polishing block is held by gravity in polishing engagement with the roll face, said pivoted arms being loosely
5 connected to the pivot support therefor, and means on said arms whereby the polishing block is swung into and out of engagement with the roll face.

In testimony whereof, we have hereunto set our hands.

OSCAR LINDQUIST.
ANDRO PISARCIK.
